SUITCASE STRUCTURE

Jerome S. Kivett, Kansas City, Mo., assignor to Regal Plastic Company, Kansas City, Mo., a corporation of Missouri

Application October 22, 1956, Serial No. 617,514

4 Claims. (Cl. 190—53)

This invention relates to improvements in receptacles or containers such as carrying cases, merchandise-receiving equipment, luggage, valises, suitcases and the like, and has for its primary object the adaptation of modern-day materials in a manner to present a strong, durable, lightweight and attractive over-all construction.

The field of the instant invention has for many years followed a more or less standard and uniform pattern, including as a basic component thereof, structural framing or boxing, usually of wood, upon which outermost coverings are subsequently placed and within which are mounted various types of linings to hide the unsightly appearance of the box or frame. Manifestly, the framework provided the necessary rigidity and could be produced without excessive weight. Furthermore, it is well understood that the materials employed for covering the frame have varied considerably and much of the luggage presently on the market is either covered with leather, imitation leathers, plastic covered fabrics or the like.

Accordingly, it is the most important object of the present invention to eliminate the disadvantages incident to the utilization of a frame support, by employment of plastic or other suitable material, capable of being bent, formed or molded into the desired shape.

Another important object of the present invention is to provide a container having a pair of hollow bodies in the usual manner, but each formed in a manner to present rounded corners and edges, thereby eliminating the time consuming, expensive and laborious task that has heretofore been necessary when using framework of wood or the like in order to present such arcuate, and therefore, attractive, configurations.

A further object of this invention is to provide a hollow body for receptacle construction made as aforementioned and having inturned flanges, one of which is utilized to quickly, easily and conveniently mount a cover and the other serving as a part of the joint between the two hollow bodies or sections of the finished article.

Other objects include important details of construction and manner of formation of structure of the kind above set forth, all of which will be made clear as the following specification progresses, reference being had to the accompanying drawing, wherein:

Figure 1 is a plan view of structure made pursuant to my present invention.

Fig. 2 is a fragmentary, cross-sectional view taken on line II—II of Fig. 1.

Fig. 3 is a fragmentary, cross-sectional view taken on line III—III of Fig. 1; and

Fig. 4 is a perspective view of the structure on a reduced scale.

As can be readily appreciated from the drawing, the structure forming the subject matter of the instant invention, consists of a pair of substantially identical, relatively shallow hollow bodies which may be conveniently designated as a top section 10 and a bottom section 12. Each may be formed from an initially flat, elongated strip of self-sustaining material that may be bent, shaped or molded into the desired configuration.

There are many plastic and other materials presently on the market having such characteristics and it is proposed in producing the two sections 10 and 12, to form the initially flat strip in the presence of sufficient heat around a suitable mold and thereupon, join the ends thereof in some satisfactory manner. For purposes of illustration, such ends are shown interconnected by overlapping straps 14 and 16 respectively, bonded or otherwise affixed to the innermost faces of the sections 10 and 12.

Referring to the section 10 thus formed, it includes therefore, a continuous band 18 that is substantially U-shaped in cross-sectional contour, thereby presenting a continuous polygonal wall 20 having a plurality of sides 22, 24, 26 and 28.

The wall 20 has a continuous, inturned, outermost flange 30 and a continuous, inturned, innermost flange 32 integral therewith, the flange 30 being preferably of an appreciably greater width than the width of the flange 32. Alternately, the band 18 may be initially U-shaped in cross-section and thereupon formed into the continuous, polygonal body as shown. A cover 34 is joined to the flange 32 in any suitable manner not shown, thereby closing one face of the body 10.

The sides 22, 24, 26 and 28 are interconnected by arcuate corners 36 and the flanges 30 and 32 are connected with the wall 20 by arcuate edges 38 and 40 respectively. Still further, one end 42 of each corner 36 is bevelled and merges arcuately therewith, as well as with the edges 38.

The bottom 12 is substantially identical with the top 10 in that there is presented a continuous band 18', having a polygonal wall 20' that includes a plurality of sides 22', 24', 26' and 28'. Flanges 30' and 32' are integral with the wall 20' and a cover 34' is suitably affixed to the flange 30'. Arcuate corners 36' interconnect the sides of the wall 20' and edges 38' and 40' are arcuate formed for purposes of appearance. Finally, the outermost ends 42' of the corners 36' are bevelled and merge with the edges 40'.

The bottom 12 differs from the top 10 only in the provision of a continuous, lateral extension 44 that overlaps the innermost edge of the flange 32 when the flanges 32 and 32' are in abutting relationship, the extension 44 being integral with the flange 32'.

The two sections 10 and 12 may be interconnected if desired for relative swinging movement through the provision of hinge means 46 and be held in a closed position by suitable clasps 48 in the conventional manner.

Still further, a handle 50 may be provided preferably on the section 12 between the clasps 48, if desired. In this respect further, it is to be recognized that many other refinements commonly employed in structure of this nature, have not been illustrated since the same form no part of the instant invention. For example, while it is contemplated that the material forming the bodies 10 and 12 be sufficiently strong in itself to withstand the uses to which the structure is to be placed, lighter weight material may be employed if desired, and subsequently reinforced within the bodies 10 and 12, particularly adjacent the carrying handle, wherever it may be placed. Additionally, it is desirable and quite conventional to line the innermost faces with attractive material if, for no other purpose than to hide the joints and other unattractive parts therewithin.

From the foregoing, it is now apparent that there has been provided a lightweight, inexpensive structure that incorporates all of the advantages, particularly from the standpoint of durability and attractiveness, of conventional construction.

2

Additionally, there has been provided a basic unit wherein all of the arcuate corners and edges have been presented without the expense and labor heretofore made necessary through use of a covered frame or box arrangement. And, as above indicated, with the basic assembly thus presented, it is well within the skill of the art to proceed with such additional adornments as is commonly employed in this particular field.

Having thus described the invention what is claimed as new and desired to be secured by Letters Patent is:

1. In suitcase structure, a top section and a bottom section, each including a hollow body provided with a continuous polygonal band having a polygonal planar portion defining a central polygonal opening, a continuous polygonal wall integral with the outermost peripheral margin of said planar portion and extending laterally therefrom in one direction and a continuous polygonal inturned flange integral with the peripheral margin of said wall remote from said planar portion, the body thereby being substantially U-shaped in transverse cross-section and a polygonal cover secured to each of said planar portions respectively in overlying, covering relationship to corresponding openings, the inturned flanges of said sections being in abutting relationship when the structure is closed.

2. Suitcase structure as set forth in claim 1 wherein said band comprises an initially flat, elongated strip of self-sustaining material having the ends thereof joined together.

3. In suitcase structure, a top section and a bottom section, each including a hollow body provided with a continuous polygonal band having a polygonal planar portion defining a central polygonal opening, a continuous polygonal wall having a plurality of sides, integral with the outermost peripheral margin of said planar portion and extending laterally therefrom in one direction and a con-

tinuous polygonal inturned flange integral with the peripheral margin of said wall remote from said planar portion, the body thereby being substantially U-shaped in transverse cross-section, said walls each having arcuate corners joining the sides thereof, there being arcuate edges between each planar portion and the sides of its corresponding wall and a polygonal cover secured to each outermost flange respectively, the inturned flanges of said sections being in abutting relationship when the structure is closed.

4. In suitcase structure, a top section and a bottom section, each including a hollow body provided with a continuous polygonal band having a polygonal planar portion defining a central polygonal opening, a continuous polygonal wall having a plurality of sides, integral with the outermost peripheral margin of said planar portion and extending laterally therefrom in one direction and a continuous polygonal inturned flange integral with the peripheral margin of said wall remote from said planar portion, the body thereby being substantially U-shaped in transverse cross-section, said walls each having arcuate corners joining the sides thereof, there being arcuate edges between each planar portion and the sides of its corresponding wall, each end of each corner being beveled and merging arcuately with said arcuate edges and corners and a polygonal cover secured to each outermost flange respectively, the inturned flanges of said sections being in abutting relationship when the structure is closed.
